UNITED STATES PATENT OFFICE.

CHARLES W. TWIGG, OF NORTH UNION, INDIANA.

IMPROVEMENT IN EARTH-AUGERS.

Specification forming part of Letters Patent No. 178,207, dated May 30, 1876; application filed April 19, 1876.

To all whom it may concern:

Be it known that I, CHARLES W. TWIGG, of North Union, in the county of Montgomery and State of Indiana, have invented certain new and useful Improvements in Post-Hole Augers; and I do hereby declare that the following is a full, clear, and exact description thereof, which will enable others skilled in the art to which it appertains to make and use the same, reference being had to the accompanying drawings, and to letters of reference marked thereon, which form a part of this specification.

My invention relates more especially to means for adjusting the bits of a post-hole auger to cut holes of various diameters, and to also permit of the removal of the bits for being sharpened when required.

The means by which I effect this adjustment are hereinafter set forth, and shown in the accompanying drawings, in which—

Figure 1 represents a perspective of a post-hole auger embracing my invention; Fig. 2, a top view, the shaft being cut off above the bits; Fig. 3, a similar view, showing the bits adjusted to cut a hole of greater diameter; Fig. 4, a bottom view, and Fig. 5 a vertical section through the bits and their cross-piece or carrier.

Referring to these drawings, A represents the shaft of a post-hole auger, and B B the disks, which have downwardly-extending and lipped cutting-bits *a a*, as usual.

The shaft A pierces and carries a cross-piece, C, extending equidistant upon each side of said shaft over the disks B, and holding them in their function and to their adjustment in the following manner: Each end of the cross-piece C has a longitudinal slot, *b b*, and each disk or semi-disk B has a slot, *c*, equal in length or nearly so to said slots *b*, and when the parts are attached the slots of the cross-piece are at right angles to the slots of the disks. The fastening of the disks and cross-piece is by square bolts *d d*, held by clamp-

nuts *e* and washers *f*, to hold the disks firmly in the desired position with reference to the cross-piece. This position is determined by the diameter of the post-hole.

In Fig. 1 the bits are shown as cutting in the same circumferential line. But in order to increase the diameter of the hole, or rather to cut a larger hole with the same auger, I loosen the clamp-nuts and move the disks outwardly—the bolts traveling in the direction of the length of the cross-piece slots, and also at right angles to said cross-piece, and in opposite directions in the length of the disk-slots. By this means the disks are separated and their bits or cutting portions each carried outside of the ordinary circumferential line of cutting, and hence, as each bit cuts in an opposite direction, the circumferential cutting-line is increased without increasing the surface of the disks themselves.

From this description it will be readily seen that a post-hole auger capable of cutting one-sized holes hitherto, may be rendered capable of cutting different sized holes by adapting my arrangement and construction of cross-piece and slots thereto.

I claim—

1. In a post-hole auger, a slot or slots in the connecting cross-piece at right angles with and in combination with slots in the disks or cutters, as and for the purpose described.

2. The combination, in a post-hole auger, of the cross-piece C, having slots *b b*, the cutters B, having slots *c* at right angles thereto, and the square bolts *d d*, said bolts clamping the cutter and cross-piece in position, as described, to effect the purpose set forth.

In testimony that I claim the foregoing I have affixed my signature in presence of two witnesses.

CHARLES WESLEY TWIGG.
